UNITED STATES PATENT OFFICE.

JACOB DIEFENBACH, OF LONG BEACH, CALIFORNIA.

METHOD OF MAKING BAS-RELIEFS.

Application filed May 17, 1926. Serial No. 109,757.

My invention relates to improvements in methods of making bas-reliefs and the object of the invention is to devise means adapted to be applied to the surface of stone, metal, 5 glass, etc., so that said surface may be submitted to the action of a sand-blast in such a manner as to produce a bas-relief of any desired design whether simple or intricate. A further and particular object of the invention is to obviate the necessity of subjecting the surface to be treated to light-rays as has been necessary in similar processes used heretofore, thus enabling my process to be used upon the surfaces of large 10 pieces of stone, etc., such as are used in monumental and similar work.

My invention consists of an improved method of making bas-reliefs all as herein-after more particularly described and illustrated in the accompanying drawing in which:

Fig. 1 is a perspective view of a fragmentary portion of a piece of paper or other similar material which is coated upon one 25 side with a sensitized paste and upon the other side with an adhesive solution.

Fig. 2 is a similar view to Figure 1 showing a portion of a stencil positioned upon the sensitized side of the paper.

Fig. 3 is a front elevational view of the fragmentary portion of paper shown in Figure 1 after the sensitized side of such paper has been subjected to actinic rays through the stencil, the stencil being removed.

Fig. 4 is a sectional view through the line 4-4 Figure 3 the paper being shown positioned upon the surface of a fragmentary portion of material such as stone.

Fig. 5 is a similar view to Figure 4 showing the assemblage after it has been subjected to the action of a sand-blast, and,

Fig. 6 is a perspective view of a fragmentary portion of the stone showing a portion of the completed bas-relief thereon.

Like characters of reference indicate corresponding parts in the different views.

In carrying out my improved method a sheet of material 1 such as blotting paper is coated upon one side with a sensitized paste 2 which is quickly soluble in water, and is adapted to be rendered practically insoluble

in water by the action of light. The other side of the material is coated with an adhesive solution 3. When it is desired to reproduce upon a surface any particular design a stencil or pattern 4 of light-transmitting material is placed upon the sensitized side 2 of the paper, the assembly then being subjected to light-rays either solar or artificial, the light-rays passing through the open portions of the stencil or the transparent portions of the pattern and acting upon and hardening the exposed portions of the paste 2. The stencil is now removed and the coated paper submerged in a cold water 65 bath, and as the portions of the solution which were not exposed to the light-rays are soluble they will be washed off leaving the light-hardened or insoluble portion of the solution upon the paper. The paper is 70 then removed from the bath and dried in the usual manner as practiced by photographers. If it is found that the bath washes away the adhesive solution 3 upon the other side of the paper, the application of such solution 75 can of course be deferred until the paper is removed from the bath and dried. It will be appreciated that the light-hardened portions of the solution left upon the paper are of the same design as the open portions 80 of the stencil, the pattern formed of the hardened portions of the solution remaining thereon as illustrated in Figure 3.

When it is desired to cut that particular pattern upon any surface it is only necessary 85 to wet the adhesive solution 3 upon the other side of the paper and paste the paper upon such surface. When the adhesive solution is thoroughly dry and the paper firmly fixed in position the cutting process may 90 then be commenced. This is achieved by a sand-blast which is directed upon the face of the paper in the direction illustrated by the arrow in Figure 4, the sand-blast quickly cutting away the portions of the paper 95 unprotected by the hardened solution and coming in contact with the surface of the object which is to be cut, such surface being in turn cut into by the sand-blast as illustrated in Figure 5 thus forming the same 100 design as that of the hardened solution-covered portion of the paper. It will be

understood that this light-hardened solution must be of sufficient hardness to withstand the sand-blast. It has been found that a solution composed of five percent of 5 potassium bichromate, four percent of glycerin, forty percent of glue and fifty-one percent of water makes an admirable compound for this purpose.

After the application of the sand-blast it 10 is of course necessary to remove the portions of paper protected by the hardened solution, this may be done by one of several methods such as thoroughly wetting it with hot water containing potash which is a solvent for the hardened solution.

I am aware that a sensitized solution and sand-blast method has been used for inscribing designs and names upon plateglass and also has been used for cutting cameos upon 20 cameo glass but it has always been necessary to apply the sensitized solution directly upon the surface to be cut which necessitates the placing of such surface in a dark room prior to its exposure to light through a stencil.

25 My method is particularly designed for use in cutting surfaces of large objects which through their bulk cannot be conveniently transported to a darkened room, and furthermore by my process a number of designs 30 can be made from the one stencil as it is only necessary to place the stencil on the sensitized side of the paper, expose the assembly to the light and after exposure return it to a dark room where the stencil can be removed and the paper immersed in a cold water bath as before described.

This process has been found particularly adaptable for monumental work where the paper upon which the pattern is outlined in 40 hard solution can be stuck upon the surface of the stone by means of the adhesive paste 3 and the sand-blast applied. Furthermore by applying the sensitized solution upon sheets of paper instead of directly upon the 45 surface to be cut it will be appreciated that I have devised means for very substantially reducing the cost of this process as any desired pattern may be printed upon a sheet of sensitized paper and such paper forwarded to any required destination.

50 As the stencil is made directly upon the sensitized side of the paper it will be seen that an extremely sharp outline will be achieved as there is no possibility of the actinic rays being deflected or shadows being cast and furthermore as the paper is comparatively thin the sand-blast will in turn cut a clear pattern upon the surface to which the paper is affixed.

55 60 What I claim as my invention is:

1. The herein described method of making bas-reliefs comprising the application of a sensitized solution upon a sheet of material, placing a pattern having transparent and

opaque portions upon the sensitized coating 65 of the sheet of material, directing actinic rays upon said coating through the pattern, removing the portions of the coating to which the rays have not penetrated, positioning said sheet of material upon the object 70 upon which it is desired to form a bas-relief and eroding by a sand-blast the portions of said surfaces which are not covered by the sensitized coated portions of the material.

2. The herein described method of making 75 bas-reliefs comprising the application of a sensitized solution upon a sheet of flexible material, placing a pattern having transparent and opaque portions upon the sensitized coating of the sheet of material, directing actinic rays upon said coating through the pattern, removing the portions of the coating to which the rays have not penetrated, positioning said sheet of material upon the object upon which it is desired to 80 form a bas-relief and eroding by a sand-blast the portions of said surfaces which are not covered by the sensitized coated portions of the material.

3. The herein described method of making 90 bas-reliefs comprising the application of a sensitized coating upon a sheet of material, positioning a pattern having transparent and opaque portions upon the sensitized coating of the sheet of material, directing actinic rays through the pattern onto said coating, removing the pattern from the sensitized coating, immersing the material in a bath to remove the portions of the coating to which the rays have not penetrated, drying said 100 material and positioning it upon the surface of the object upon which it is desired to form a bas-relief, and eroding by a sand-blast the portions of said surfaces which are not covered by the sensitized coated portions 105 of the material.

4. The herein described method of making bas-reliefs comprising the application of a sensitized coating to one side of a flexible sheet of material, applying an adhesive solution to the other side of the material, placing a pattern having transparent and opaque portions upon the sensitized coating of the sheet of material, directing actinic rays upon 110 said coating through the pattern, removing the portions of the coating to which the rays have not penetrated, adhering the adhesive solution-covered side of the material to the surface of the object upon which it is desired to form a bas-relief, and eroding by a sand-blast the portions of said surfaces which are not covered by the sensitized coated portions 115 of the material.

5. The herein described method of making 120 bas-reliefs comprising the application of a sensitized coating to the material, positioning a pattern having transparent and opaque portions upon the sensitized coating of the

sheet of material, directing actinic rays through the pattern onto said coating, removing the pattern from the sensitized coating, immersing the material in a bath to remove the portions of the coating to which the rays have not penetrated, adhering the adhesive solution-covered side of the mate-

rial to the surface of the object upon which it is desired to form a bas-relief and eroding by a sand-blast the portions of said surfaces which are not covered by the sensitized 10 coated portions of the material.

JACOB DIEFENBACH.
